UNITED STATES PATENT OFFICE.

WILLIAM HENRY SNYDER, OF SAN FRANCISCO, CALIFORNIA.

LAST.

SPECIFICATION forming part of Letters Patent No. 283,826, dated August 28, 1883.

Application filed June 23, 1883. (No model.)

To all whom it may concern:

Be it known that I, WILLIAM H. SNYDER, of San Francisco, in the county of San Francisco and State of California, have invented certain new and useful Improvements in Shoe-Makers' Lasts; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical sectional view of my improved last. Figs. 2 and 3 are perspective views of the two parts of the last separated, and Figs. 4 and 5 are perspective detail views of the locking devices detached.

Similar letters of reference indicate corresponding parts in all the figures.

20 My invention has relation to shoe-makers' lasts; and it consists in the improved construction and combination of parts of the fastenings for attaching the block to the body of the last, as hereinafter more fully described and claimed.

In the accompanying drawings, the letter A indicates the body of the last, and B the block, which fits into the recess C in the top of the body of the last, both of which parts are of 30 the usual construction. The edges D of the point of the block are beveled, and fit under the correspondingly-beveled end, E, of the recess C, thus holding the point of the block in place, and the rear end of the block is held in 35 place by means of a triangular plate, F, beveled at its forward pointing sides, fastened to a plate, G, secured to the underside of the block, by means of screws H, and fitting into a correspondingly-beveled triangular slot, I, in the 40 rear end of a plate, J, which is fastened in a recess, K, in the upper rear portion of the recess C, so that the triangular beveled plate may be inserted into the slot from the rear end of recess C. Inside plate G is a plate, L, the 45 forward end of which forms two ears or lugs, M, between which a lever, N, bent at a right angle, is pivoted at its knee, projecting into a recess, O, in the block. A spring, P, fastened to plate L, bears with its free end against the 50 upwardly-pointing arm of the lever against its rear edge, and the forwardly-pointing arm

of the lever is provided with a downwardly-pointing lug, Q, which projects and catches into a perforation, R, in the forward end of plate J, thus preventing the block from being withdrawn when caught. To unlock this catch the last-key is inserted into the transverse perforation S in the upper portion of the block, which is usually found in all lasts, and the recess O is so located that its upper end is 60 transversed by the perforation S, and the upwardly-pointing arm of the lever projects into the said perforation, so that it is tilted rearward when the last-key is inserted, lifting the lug or catch upon its other end up out of the 65 perforation in the plate upon the body of the last. In this manner it will be seen that the block is released from the body of the last in the moment the last-key is inserted, allowing it to be withdrawn, while it will remain firmly 70 locked in place after it has been inserted, and the triangular plate and the slot, having their edges beveled, will allow the block to be easily inserted and withdrawn, and will hold the block firmly in place, the beveled edges wearing to 75 a seat by use without becoming worn, so as to fit loosely.

Having thus described my invention, I claim and desire to secure by Letters Patent of the United States—

1. The combination of the body of the last, having the usual recess in its upper side, the plate having the triangular slot in its rear end, said slot having beveled edges, and having the perforation in its forward end, for the purpose 85 set forth, and fastened in a smaller longitudinal recess in the upper end of the larger recess in the upper portion of the body of the last, the triangular plate having beveled edges and fastened to a plate secured to the block at 90 the rear end of its under side, the block having a recess in its under side for the reception of the locking-lever, and a transverse perforation for the insertion of the last-key at the rear end of its under side, and the locking-lever, bent at a right angle, pivoted between 95 two ears upon a plate fastened to the under side of the block, and having a downwardly-projecting lug upon its forwardly-pointing arm and a spring bearing against the rear edge 100 of its upwardly-pointing arm, as and for the purpose shown and set forth.

2. The combination of the body of the last, having the recess in its upper portion, having the beveled forward end, the plate having the triangular beveled slot at its rear end and the perforation at its forward end, as described, 5 the triangular plate fastened to the rear end of the under side of the block, the block, and the locking-lever having a downwardly-projecting lug engaging the perforation in the end of 10 the plate upon the body of the last, and having its upper end projecting into the transverse

perforation in the block for the insertion of the last-hook, as and for the purpose shown and set forth.

In testimony that I claim the foregoing as 15 my own I have hereunto affixed my signature in presence of two witnesses.

WILLIAM HENRY SNYDER.
